UNITED STATES PATENT OFFICE

AUGUST ENSTROM, OF CHICAGO, ILLINOIS, ASSIGNOR TO PETTIBONE MULLIKEN COMPANY, OF CHICAGO, ILLINOIS, A CORPORATION OF DELAWARE

SPLIT-SWITCH STRUCTURE

Application filed May 31, 1930. Serial No. 458,625.

My invention relates more particularly to split-switch structures comprising point-rails each mounted at one end for swinging movement into and out of switching position and restrained against lengthwise displacement by bolts, or the like, extending therethrough crosswise of the point-rails and the rails adjacent to the latter.

Certain of my objects are to eliminate the necessity for use of the thimbles commonly used in structures of this character, thereby reducing the number of parts required for the switch assembly, eliminating the hazard of losing the thimbles by the sliding thereof into the holes provided in the heel fillers when used, and avoiding impairment of the switch structure by breakage of the thimbles which often occurs; to provide a stronger and more durable switch structure of the character above stated and the parts of which may be assembled with greater facility; to provide a pivoting structure for the point-rail which will be less liable to become impaired in use and thus render the switch structure more safe; to provide a structure insuring a tight joint adjacent the heel portion of the point-switch; to provide a structure requiring the minimum servicing in use; to provide for the elimination of the counterboring of the angle bars of the switch structure usually required in structures of this general character as hitherto provided; and other objects as will be manifest from the following description.

Referring to the accompanying drawings:

Figure 1 is a plan view of a railway track construction provided with a split-switch structure constructed in accordance with my invention.

Figure 2 is a plan view of a portion of the switch structure of Fig. 1, with the portion of the structure at the pivot for the point rail shown in section.

Figure 3 is an enlarged section taken at the line 3 on Figs. 1 and 2 and viewed in the directions of the respective arrows.

Figure 4 is a broken plan view, partly sectional, of a modification of the structure

shown in Figs. 2 and 3, and embodying my invention.

Figure 5 is a view like Fig. 2 of another modified form of switch structure embodying my invention; and

Figure 6, an enlarged section taken at the line 6 on Fig. 5 and viewed in the direction of the arrow.

Referring to the track construction shown in Figs. 1, 2 and 3, 10 indicates one of the rails of a main track the other portion thereof comprising a rail 11, a point-rail 12 of my improved switch structure and a rail 13, the rail 11 continuing from the point-rail 12 in deflected condition, as represented at 14 to form one of the rails of a switch track.

A point-rail switch comprises the point-rail 12 and a point-rail 15 adjacent the main rail 10, these point-rails being connected together by a tie rod 16 and also adjacent the pointed extremities of the point-rails by a head-rod 17 which latter, in practice, would be connected with any suitable switch-throwing mechanism (not shown).

Positioned at the heel of the point-rail 15 is a rail 18 which parallels the switch-track rail 14 and forms the other rail of the switch-track.

In constructions of this general character the point-rails are pivoted at their heel portions to adapt them to be swung into and out of switching position, the means shown for permitting the point-rails to be swung for the purpose stated and preventing lengthwise movement of these rails and constituting an embodiment of my invention being as follows:

Interposed between the rail 10 and the adjacent ends of the rails 15 and 18 is a filler-block 19 and extending across the joint between the rails 15 and 18, at the inner side of the track, is an angle bar 20 and at the outer side of the rail 10, a plate (not shown) fitting against its web. A similar filler block 21 is located between the rail 14 and the adjacent ends of the rails 12 and 13, with an angle bar 22 extending across the joint between the rails 12 and 13, at the inner side of the track and

a plate 14^a at the outer side of the rail 14 and fitting against its web.

As the construction of means for permitting the swinging of the point-rails 12 and 15 and preventing lengthwise movement thereof is the same as to both point-rails, the means at the point-rail 12 only will be described in detail.

Referring to these means for the point-rail 12, the filler block 21, rails 13 and 14, angle bar 22 and plate 14^a are rigidly secured together by a series of bolts 23 extending through these parts, and the filler block 21, rail 14 and plate 14^a are also clamped together by a bolt represented at 24 and hereinafter described, the left-hand end of the bar 22 being deflected inwardly as represented at 25 to provide between it and the filler block 21 a recess 26 into which the heel of the point-rail 12 extends, this recess being of such width that the point-rail is free to swing in a horizontal plane, the bolt 24 also extending through the deflected end 25 of the bar 22.

A fourth, plain, bolt 23^a is shown as extending through the angle bar 22, filler block 21, rail 14, plate 14^a, and loosely through an opening in the heel of the point-rail 12, this bolt exerting a clamping action between the deflected end 25 of the angle bar 22, and the plate 14^a, without clamping the point-rail 12. The bolt 24 is shown as of the type which is threaded at its opposite ends as represented at 27 and 28 with nuts 29 and 30, respectively, screwed thereon, the bolt 24 presenting a pair of shoulders 31 and 32 rigid therewith between its threaded portions. The threaded portion 28 of the bolt extends through the deflected end 25 of the bar 22, which latter is clamped between the shoulder 32 and the nut 30, a spring washer 34 being confined between the nut 30 and the bar 22. The portion of the bolt between the shoulders 31 and 32 extends loosely through an opening 35 in the web of the heel portion of the point-rail 12; and the end of the bolt 24 beyond the shoulder 31 extends through the filler block 21, rail 14, and plate 14^a. The shoulder 31 abuts the inner side of the filler block 21 and upon tightening the nut 29, a spring washer 36 being interposed between the nut 29 and the plate 14^a, the parts 21, 14, and 14^a are rigidly clamped together, the spring washer 36 becoming tensioned and the deflected portion 25 of the bar 22 slightly sprung to the left in Fig. 3.

The bolt 24 may be of any suitable form to provide the shoulders 31 and 32. Preferably these shoulders are formed by providing the bolt with the portion of greater cross sectional area represented at 37 and which, as shown, may be and preferably is, of circular shape in cross section, at which portion

the bolt extends through the opening 35 in the point rail 12.

In Fig. 4 I have illustrated the use of another type of bolt in carrying out my invention, this other type being of a form provided with an integral head and an enlarged part adjacent thereto and presenting a shoulder. This bolt, in Fig. 4, is shown as substituted for the bolt 24 in the switch assembly of Figs. 2 and 3, to the corresponding parts of which in Fig. 4 the same numerals are applied. The bolt of Fig. 4 and shown at 38 has a head 39 integral therewith at one end and is threaded at its opposite end as represented at 40 to receive a nut 41. The bolt is formed to provide thereon a rigid shoulder 42 corresponding with the shoulder 31 of the bolt 24 of Figs. 2 and 3 and bearing against a side of the filler block 21, the head 39 of the bolt bearing against the outer face of the deflected portion 25 of the bar 22. The nut 41, upon being screwed on the threaded end 40 of the bolt and against a spring washer 43, clamps together the filler block 21, rail 14, and plate 14^a, tensioning the washer 43 and slightly springing the deflected end 25 of the bar 22 in a direction toward the filler block 21.

The shoulder 42 is shown as formed by providing the bolt with a portion 44 of enlarged cross-sectional area, preferably cylindrical, at which the bolt extends through the opening 35 in the heel portion of the point rail 12.

In some constructions of split-switches 100 filler blocks positioned as shown and described with respect to the filler blocks 19 and 21 are omitted and the bolts extending through the heel portions of the point-rails are mounted in bars located at opposite sides of the rails which oppose the heel portions in end-to-end relation and as illustrating an embodiment of my invention in a switch structure of this particular construction reference is made to Figs. 5 and 6 of the 110 drawings which represent the portion of a railway track corresponding with that disclosed in the upper part of Fig. 1. In this construction the main rail corresponding with the main rail 10 of Fig. 1, is represented at 45 and the point-rail and switch rail corresponding with the rails 15 and 18 in Fig. 1, are represented at 46 and 47, respectively.

In this construction the joint between the rails 46 and 47 is spanned by angle bars 48 and 49, the end of the bar 49 which extends along the rail 46 being bent to incline away from this rail at the portion thereof represented at 50, the bars 48 and 49 being rigidly clamped against the opposite sides of the rail 47 by bolts represented at 51.

The ends of the bars 48 and 49 projecting beyond the adjacent end of the rail 47 form a recess 52 into which the heel portion of the

point-rail 46 extends, this recess being of such width as to permit the point-rail 46 to swing horizontally therein.

Extending through the projecting ends of the bars 48 and 49 and loosely through an opening 53 in the hollow portion of the point rail 46, is a bolt 54 of the same general form as the bolt 24 and having a shoulder 55 between which and a nut 56 screwed on the threaded end 57 of this bolt, the bar 48 is clamped, with a spring washer 58 interposed between the nut 56 and a bar 48. The bolt 54 is also threaded at its opposite end as represented at 59 to receive a nut 60 and is provided adjacent thereto with a second shoulder 61, the bolt 54 extending at its threaded end 59, through the bar 49 which latter is clamped between the shoulder 61 and the nut 60, with a spring washer 62 interposed between the bar 41 and the nut 60, the deflected portion 50 of the bar 49 being slightly sprung toward the point rail 46 upon tightening the nut 60.

The bolt 54 may be of any suitable form to provide the shoulders 55 and 61, in the construction shown these shoulders being provided by forming the bolt with the portion of greater cross sectional area represented at 63 and which, as shown, may be circular in cross section, at which portion the bolt 54 extends through the opening 53 in the point rail 46.

A fourth, plain, bolt 64 is shown as extending through the bars 48 and 49 and loosely through the heel portion of the point-rail 46 for stiffening the construction, but without clamping the point rail 46.

It will be understood that, if desired, a bolt of the type shown in Fig. 4 may be used in the construction of Figs. 5 and 6 instead of the bolt therein shown.

By constructing a switch structure in accordance with my invention the use of thimbles is avoided with their attendant disadvantages and without increasing the cost of the construction.

While I have illustrated and described certain embodiments of my invention, I do not wish to be understood as intending to limit my invention thereto as the invention may be embodied in other forms of structure and those shown may be variously modified and altered without departing from the spirit of my invention.

What I claim as new, and desire to secure by Letters Patent, is:

1. Point switch mechanism comprising a structure presenting spaced-apart portions forming a recess, a point-rail extending at its heel portion into said recess and swingable therein, and a bolt having a nut at one end and extending through said spaced-apart portions and loosely through said heel-portion, said bolt having a fixed shoulder thereon located at one side of one of said

spaced-apart portions, said nut being located at the opposite side of said last-referred-to portion and when tightened drawing said shoulder into engagement with said last-referred-to portion.

2. Point switch mechanism comprising a structure presenting spaced-apart portions forming a recess, a point-rail extending at its heel portion into said recess and swingable therein, and a bolt having a nut at one end and extending through said spaced-apart portions and loosely through said heel-portion, said bolt having a fixed shoulder thereon located at one side of one of said spaced-apart portions, said nut being located at the opposite side of said last-referred-to portion and when tightened drawing said shoulder into engagement with said last-referred-to portion, said bolt at its opposite end engaging the other of said spaced-apart portions.

3. Point switch mechanism comprising a structure presenting spaced-apart portions forming a recess, a point-rail extending at its heel portion into said recess and swingable therein, and a bolt having nuts at its opposite ends and extending through said spaced-apart portions and loosely through said heel-portion, said bolt having fixed oppositely facing shoulders between said nuts and located at the inner sides of said spaced-apart portions, said nuts being located at the outer sides of said spaced-apart portions and when tightened drawing said shoulders into engagement with said last-referred-to portions.

4. Point switch mechanism comprising a structure presenting spaced-apart portions forming a recess, a point-rail extending at its heel portion into said recess and swingable therein, and a bolt having a nut at one end and extending through said spaced-apart portions and loosely through said heel-portion, said bolt having a fixed shoulder thereon located at one side of one of said spaced-apart portions, said nut being located at the opposite side of said last-referred-to portion and when tightened drawing said shoulder into engagement with said last-referred-to portion, said bolt at its opposite end engaging the other of said spaced-apart portions and in the adjusting of said nut to set position springing one of said spaced-apart portions toward the other thereof.

5. Point switch mechanism comprising a structure presenting spaced-apart portions forming a recess, a point-rail extending at its heel portion into said recess and swingable therein, and a bolt having nuts at its opposite ends and extending through said spaced-apart portions and loosely through said heel-portion, said bolt having fixed oppositely facing shoulders between said nuts and located at the inner sides of said spaced-apart portions, said nuts being located at

the outer sides of said spaced-apart portions and when tightened drawing said shoulders into engagement with said last-referred-to portions and springing one of said spaced-apart portions toward the other thereof.

6. Point switch mechanism comprising a structure presenting spaced-apart portions forming a recess, a point-rail extending at its heel portion into said recess and swingable therein, a bolt having a nut at one end and extending through said spaced-apart portions and loosely through said heel-portion, said bolt having a fixed shoulder thereon located at one side of one of said spaced-apart portions, said nut being located at the opposite side of said last-referred-to portion, and a spring washer on said bolt between said nut and said last-referred-to portion, said shoulder during the tightening of said nut being drawn against said last-named portion and said washer becoming tensioned.

7. Point switch mechanism comprising a structure presenting spaced-apart portions forming a recess, a point-rail extending at its heel portion into said recess and swingable therein, a bolt having a nut at one end and extending through said spaced-apart portions and loosely through said heel-portion, said bolt having a fixed shoulder thereon located at one side of one of said spaced-apart portions, said nut being located at the opposite side of said last-referred-to portion, said bolt at its opposite end engaging the other of said spaced-apart portions, and a spring washer on said bolt between said nut and the one of said spaced-apart portions adjacent thereto, said shoulder during the tightening of said nut being drawn against said last-named portion and said washer becoming tensioned.

8. Point switch mechanism comprising a structure presenting spaced-apart portions forming a recess, a point-rail extending at its heel portion into said recess and swingable therein, a bolt having a nut at one end and extending through said spaced-apart portions and loosely through said heel-portion, said bolt having a fixed shoulder thereon located at one side of one of said spaced-apart portions, said nut being located at the opposite side of said last-referred-to portion, said bolt at its opposite end engaging the other of said spaced-apart portions, and a spring washer on said bolt between said nut and the one of said spaced-apart portions adjacent thereto, said shoulder during the tightening of said nut being drawn against said last-named portion and said washer becoming tensioned, one of said spaced-apart portions being sprung toward the other thereof in tightening said nut.

9. Point switch mechanism comprising rails spaced apart one of which is a main rail and the other a switch rail, a filler-block

between said rails, a bar at a side of one of said rails and projecting beyond its end and forming, with said block, a recess, means securing said rails, block and bar together, a point rail extending at its heel portion into said recess and swingable therein, and a bolt having a nut at one end and extending loosely through said heel portion and having a shoulder fixed thereon and between which and said nut said filler-block and the one of said rails other than the one thereof beyond which said bar projects extend and are clamped.

10. Point switch mechanism comprising rails spaced apart one of which is a main rail and the other a switch rail, a filler-block between said rails, a bar at a side of one of said rails and projecting beyond its end and forming, with said block, a recess, means securing said rails, block and bar together, a point rail extending at its heel portion into said recess and swingable therein, and a bolt having a nut at one end and extending through the projecting end of said bar, block, and the one of said rails other than the one thereof beyond which said bar projects and loosely through said heel portion, said bolt having a fixed shoulder thereon located at the side of said block facing said bar, said nut being located at the side of said last-referred-to rail opposite that along which said block extends and when tightened drawing said shoulder against said block.

11. Point switch mechanism comprising rails spaced apart one of which is a main rail and the other a switch rail, a filler-block between said rails, a bar at a side of one of said rails and projecting beyond its end and forming, with said block, a recess, means securing said rails, block and bar together, a point rail extending at its heel portion into said recess and swingable therein, and a bolt having a nut at one end and extending through the projecting end of said bar, block and the one of said rails other than the one thereof beyond which said bar projects and loosely through said heel portion, said bolt having a fixed shoulder thereon located at the side of said block facing said bar, said nut being located at the side of said last-referred-to rail opposite that along which said block extends and when tightened drawing said shoulder against said block, said bolt at its opposite end engaging the projecting end portion of said bar.

12. Point switch mechanism comprising rails spaced apart one of which is a main rail and the other a switch rail, a filler-block between said rails, a bar at a side of one of said rails and projecting beyond its end and forming, with said block, a recess, means securing said rails, block and bar together, a point rail extending at its heel

portion into said recess and swingable therein, and a bolt having nuts at its opposite ends and extending through said spaced apart portions and loosely through said heel portion, said bolt having fixed shoulders 5 between said nuts, said filler-block and the one of said rails other than the one thereof beyond which said bar projects being clamped between one of said nuts and one of said shoulders, the other of said shoulders 10 and the other of said nuts extending at opposite sides of said bar.

13. Point switch mechanism comprising rails spaced apart one of which is a main rail and the other a switch rail, a filler-block 15 between said rails, a bar at a side of one of said rails and projecting beyond its end and forming, with said block, a recess, means securing said rails, block and bar together, a point rail extending at its heel portion into said recess and swingable 20 therein, and a bolt having a nut at one end and extending through the projecting end of said bar, block and the one of said rails other than the one thereof beyond which said bar projects and loosely through said heel portion, said bolt having a fixed shoulder thereon located at 25 the side of said block facing said bar, said nut being located at the side of said last-referred-to rail opposite that along which said block extends and said bolt at its opposite end engaging the projecting end of said 30 bar, and a spring washer on said bolt between said nut and said last-referred-to rail, said shoulder during the tightening of said nut being drawn against said block and said washer becoming tensioned. 35

14. Point switch mechanism comprising rails spaced apart one of which is a main rail and the other a switch rail, a filler-block 40 between said rails, a bar at a side of one of said rails and projecting beyond its end and forming, with said block, a recess, means securing said rails, block and bar together, a point rail extending at its heel portion 45 into said recess and swingable therein, a bolt having a nut at one end and extending through the projecting end of said bar, block and the one of said rails other than the one thereof beyond which said bar projects and loosely through said heel portion, said bolt having a fixed shoulder thereon located at the side of said block facing said bar, said nut being located at the side of said last-referred-to rail opposite that along which said block extends and when tightened drawing said shoulder against said block, said bolt at its opposite end engaging the projecting end portion of said bar and in the adjusting of said nut to set position springing said projecting end portion of said bar toward said filler-block. 50

15. Point switch mechanism comprising rails spaced apart one of which is a main rail and the other a switch rail, a filler-block 55 between said rails, a bar at a side of one of said rails and projecting beyond its end and forming, with said block, a recess, means securing said rails, block and bar together, a point rail extending at its heel portion into said recess and swingable therein, a bolt having a nut at one end and extending through the projecting end of said bar, block and the one of said rails other than the one thereof beyond which said bar projects and loosely through said heel portion, said bolt having a fixed shoulder thereon located at the side of said block facing said bar, said bolt having a part which laps the side of said last-referred-to rail opposite that along which said block extends, and a spring washer on said bolt between said nut and said last-referred-to rail, said shoulder during the tightening of said nut being drawn against said block and said washer becoming tensioned. 60

16. Point switch mechanism comprising rails spaced apart one of which is a main rail and the other a switch rail, a filler-block 65 between said rails, a bar at a side of one of said rails and projecting beyond its end and forming, with said block, a recess, means

said rails and projecting beyond its end and forming, with said block, a recess, means securing said rails, block and bar together, a point rail extending at its heel portion into said recess and swingable therein, a bolt having a nut at one end and extending through the projecting end of said bar, block and the one of said rails other than the one thereof beyond which said bar projects and loosely through said heel portion, said bolt having a fixed shoulder thereon located at the side of said block facing said bar, said nut being located at the side of said last-referred-to rail opposite that along which said block extends and said bolt at its opposite end engaging the projecting end of said bar, and a spring washer on said bolt between said nut and said last-referred-to rail, said shoulder during the tightening of said nut being drawn against said block and said washer becoming tensioned. 70

17. Point switch mechanism comprising a structure presenting spaced-apart portions forming a recess, a point-rail extending at its heel portion into said recess and swingable therein, and a bolt having a nut at one end and extending through said spaced-apart portions and loosely through said heel portion, said bolt at the portion thereof which extends through said heel portion being of enlarged cross-sectional area 90 and presenting a shoulder located at one side of one of said spaced-apart portions, said nut being located at the opposite side of said last-referred-to portion and when tightened drawing said shoulder into engagement with said last-referred-to portion. 95

18. Point switch mechanism comprising rails spaced apart one of which is a main rail and the other a switch rail, a filler-block between said rails, a bar at a side of one of said rails and projecting beyond its end and forming, with said block, a recess, means securing said rails, block and bar together, a point rail extending at its heel portion into said recess and swingable therein, and a bolt having a nut at one end extending through the projecting end of said bar, block and the one of said rails other than the one thereof beyond which said bar projects and loosely through said heel portion, said bolt at the portion thereof which extends through said heel portion being of enlarged cross-sectional area and presenting a shoulder located at the side of said block facing said bar, said nut being located at the side of said last-referred-to rail opposite that along which said block extends and when tightened drawing said shoulder against said block. 110

19. Point switch mechanism comprising rails spaced apart one of which is a main rail and the other a switch rail, a filler-block between said rails, a bar at a side of one of said rails and projecting beyond its end and forming, with said block, a recess, means

securing said rails, block and bar together, a point rail extending at its heel portion into said recess and swingable therein, and a bolt having nuts at its opposite ends and extending through said spaced apart portions and 5 loosely through said heel portion, said bolt at the portion thereof which extends through said heel portion being of enlarged cross-sectional area and presenting fixed shoulders between said nuts, said filler-block and the 10 one of said rails other than the one thereof beyond which said bar projects being clamped between one of said nuts and one of said shoulders, the other of said shoulders and the other of said nuts extending at 15 opposite sides of said bar.

19. Point switch mechanism comprising a structure presenting spaced-apart portions forming a recess, a point-rail extending at its heel portion into said recess and swingable therein, and a bolt having a nut at one end and a head at its opposite end and extending through said spaced-apart portions and loosely through said heel-portion, said bolt having a fixed shoulder thereon located 25 at one side of one of said spaced-apart portions, said nut being located at the opposite side of said last-referred-to portion and when tightened drawing said shoulder into 30 engagement with said last-referred-to portion, the head of said bolt engaging the other of said spaced-apart portions.

20. Point switch mechanism comprising a structure presenting spaced-apart portions forming a recess, a point-rail extending at 35 its heel portion into said recess and swingable therein, and a bolt having a nut at one end and a head at its opposite end and extending through said spaced-apart portions and loosely through said heel-portion, said bolt having a fixed shoulder thereon located 40 at one side of one of said spaced-apart portions, said nut being located at the opposite side of said last-referred-to portion and when tightened drawing said shoulder into 45 engagement with said last-referred-to portion, the head of said bolt engaging the other of said spaced-apart portions and in the adjusting of said nut to set position springing 50 one of said spaced-apart portions toward the other thereof.

21. Point switch mechanism comprising a structure presenting spaced-apart portions forming a recess, a point-rail extending at 55 its heel portion into said recess and swingable therein, a bolt having a nut at one end and a head at its opposite end and extending through said spaced-apart portions and loosely through said heel-portion, said bolt having a fixed shoulder thereon located 60 at one side of one of said spaced-apart portions, said nut being located at the opposite side of said last-referred-to portion, the head of the bolt engaging the other of said spaced- 65 apart portions, and a spring washer on said

bolt between said nut and the one of said spaced-apart portions adjacent thereto, said shoulder during the tightening of said nut being drawn against said last-named portion and said washer becoming tensioned. 70

22. Point switch mechanism comprising rails spaced apart one of which is a main rail and the other a switch rail, a filler-block between said rails, a bar at a side of one of said rails and projecting beyond its end and forming, with said block, a recess, means securing said rails, block and bar together, a point rail extending at its heel portion into said recess and swingable therein, and a bolt having a nut at one end and a head at its opposite end and extending through the projecting end of said bar, block and the one of said rails other than the one thereof beyond which said bar projects and loosely through said heel portion, said bolt having a fixed shoulder thereon located at the side of said block facing said bar, said nut being located at the side of said last-referred-to rail opposite that along which said block extends and when tightened drawing said shoulder against said block, the head of said bolt engaging the projecting end portion of said bar. 80
